UNITED STATES PATENT OFFICE

CONRAD DIEHL, OF HEROLDSBERG, GERMANY

BANDAGE

Application filed February 5, 1931, Serial No. 513,845, and in Germany November 5, 1930.

This invention relates to bandages and more especially to bandages which may be used as a lady's belt or as a dressing for infants and consists essentially in an improved bandage of this kind in which there is used a pocket or hull which may be made from fabric or the like and a filling consisting of a pile of superposed foils of cellular material provided with special inwardly directed curvatures at its opposite longitudinal edges.

A modified form of construction of the new bandage consists therein that said inwardly directed curvature at the longitudinal edges of said filling is of such conformation that it will subdivide said filling into a front and a rear flap of even size.

A further modified form of construction of the new bandage consists therein that the aforesaid curvature is displaced from the transverse central line of the filling so that there will be formed a front and a rear flap of different length and eventually also of different width.

A further modified form of construction of the new bandage consists therein that the pocket or hull for the filling is so constructed that it will span the aforesaid curvatures of said filling over a certain length thereof thus giving the bandage additional consistency during use.

Bandages of the present kind are known which consist of a pocket or hull of gauze with a filling of superposed foils of cellular material therein said filling forming an oblong strip inserted into said hull and having straight longitudinal edges, thus likewise determining the straight form of said hull along said straight longitudinal edges.

The bandage forming part of my invention now is of improved construction resulting in the advantage that the bandage can no more slip or otherwise be displaced during use, this being due to the presence of the aforementioned curvatures on the longitudinal edges of the filling in connection with the longitudinal edges of the bandage as a whole. Owing to the additional resiliency obtained in this manner the bandage can no more injure the skin or cause inflammations.

Besides, the new bandage on account of the aforementioned curvatures at the longitudinal edges of the filling will properly fit the body and particularly the form of the legs and prevent an undesirable compression of the bandage therebetween especially near the middle part of the latter.

My new bandage may also be used with advantage as a dressing for infants, especially as a substitute for swaddling clothes or the like. The bandage in this case permits being securely fit to the body of the infant without exerting any disagreeable pressure on the body of the infant and without causing any molestation to the latter.

In the accompanying drawing I have shown some preferred forms of my new bandage, Fig. 1 being a perspective view of the spread apart hull or pocket which when properly folded together will form a receptacle for the filling which consists of a pad or pile of superposed foils of cellular material, Fig. 2, a perspective view of Fig. 1 in properly folded condition with the filling enclosed, Fig. 3, a top-view on a filling of somewhat modified form and Fig. 4, a pocket or hull for said filling, said pocket or hull being of the shape of a hose.

Referring now more particularly to the drawing, the filling *b* which consists of a pad or pile of superposed foils of cellular material is of reduced width at its middle portion by giving an inward curvature to both longitudinal edges of said filling with the result of obtaining a filling having a middle portion of smaller width. The pocket or hull *a* which may preferably be made from gauze is folded together according to Fig. 2 in well-known manner to enclose the pad or filling *d*, preferably in such a manner that the longitudinal edges of said hull or pocket will span and fill up the curvatures at the middle part of said pad or filling thus providing for additional lateral resiliency of the bandage as a whole near the relatively rigid curved edges of the filling.

The curvatures at the middle portion of the filling *b* may, for instance, be of the smooth form shown in Figs. 1 and 2 or also

of a sharper form as indicated in Fig. 3. If the smallest width of the filling *b* is positioned centrally of the length thereof, such as is shown in Figs. 1 and 2, there will be formed at the front and rear end of said filling two flaps of even size, while if the smallest width of the filling *b* is positioned out of the center of the length of the filling there will be obtained two flaps *b*¹, *b*² of different length which, in addition, may also be of different width as shown in Fig. 3. This latter form of filling is especially suitable and advantageous if the bandage is used as a dressing for infants instead of swaddling clothes.

The new bandage or dressing may be fixed to the body of the person or infant in any desired manner, for instance, by using the lateral ends of the hull or pocket which project beyond the filling for fastening supporting strips thereto.

The bandage, however, may also be provided with a band *c* which is drawn through an aperture provided at either end of the filling and the hull as indicated in Fig. 2, and fixed with its free ends to a supporting belt.

Instead of the hull *a* which is formed from an originally flat piece of fabric or the like, as shown in Fig. 1, and folded together in the manner shown in Fig. 2, there may also be provided a hull or pocket in the form of a hose *a*¹ into which the filling may be inserted as indicated in Figs. 3 and 4.

I claim:

In a bandage of the character described, in combination, a set of superposed layers of shaped oblong pieces of cellular material, the middle portions of the longitudinal side edges of said set of layers being cut away to form restricted neck portions, and a soft and yielding envelope having parallel sides enclosing the said set of layers on all sides and extending from one end thereof to the other end of the same and across said restricted neck portion so as to enclose the latter and be substantially spaced therefrom and form therewith opposite spaces adapted to receive the adjacent spaced portions of the envelope therein when in the position of use to prevent contact of the layers with the skin of the user.

In testimony whereof I affix my signature.
CONRAD DIEHL.
